(No Model.)

S. BERGMANN.
AUTOMATIC ELECTRIC SWITCH.

No. 461,791.

Patented Oct. 20, 1891.

UNITED STATES PATENT OFFICE.

SIGMUND BERGMANN, OF NEW YORK, N. Y., ASSIGNOR TO THE BERGMANN MANUFACTURING COMPANY, OF SAME PLACE.

AUTOMATIC ELECTRIC SWITCH.

SPECIFICATION forming part of Letters Patent No. 461,791, dated October 20, 1891.

Application filed February 25, 1891. Serial No. 382,693. (No model.)

To all whom it may concern:

Be it known that I, SIGMUND BERGMANN, of New York, in the county and State of New York, have invented a certain new and useful 5 Improvement in Automatic Switches, of which the following is a specification.

I will describe an apparatus embodying my improvement, and then point out the novel features in a claim.

10 In the accompanying drawings, Figure 1 is a diagram of an apparatus embodying my improvement. Fig. 2 is an enlarged front view of an automatic switch included in said apparatus, the front of its box being removed.

15 Similar letters and figures of reference designate corresponding parts in all the figures.

A designates a dynamo-electric machine of any desired form. A wire 1 leads from one of the brushes of the dynamo and terminates

20 in a metal contact-piece 2. Adjacent to the contact-piece 2 is a similar contact-piece 3. From the contact-piece 3 a wire 4 extends. A wire 5 extends near the wire 4, and a number of electric lamps 6 are shown as con-

25 nected in multiple arc with these wires 4 and 5. The wire 5 at one end terminates in a contact-piece 7, which may be like the contact-pieces of the style mentioned. A contact-piece 8 is arranged adjacent to the contact-

30 piece 7. The contact-pieces 2 and 3 may be electrically connected and the contact-pieces 7 and 8 electrically connected by means of a switch B, here shown as consisting of a lever carrying the armature c of an electro-magnet

35 C and provided with contact-pieces b' b². The electro-magnet C attracts its armature c in a direction to cause the contact-piece b' to impinge upon the contact-pieces 2 and 3, so as to establish electrical communication be-

40 tween them and the contact-piece b², to impinge upon the contact-pieces 7 and 8 to establish electrical communication between the latter. Of course the contact-pieces b' b² must be insulated from each other. When the mag-

45 net C is de-energized a spring c' retracts the lever B, so as to move its contact-piece b' away from the contact-pieces 2 3 and its contact-piece b² away from the contact-pieces 7

and 8. From the contact-piece 8 a wire 9 extends to one end of the coils of an electro- 50 magnet D. The other end of the coils of this electro-magnet is connected to a wire 10, which extends to the other brush of the dynamo from that with which the wire 1 communi- 55 cates. Obviously, whenever the electro-mag- net C attracts its armature a circuit will be established from the dynamo through the wire 1 to the contact-piece 2, along the latter to the contact-piece b', from this contact-piece to the contact-piece 3, from the latter along 60 the wire 4 thence through the electric lamps 6, from the latter along the wire 5, contact- piece 7, contact-piece b², contact-piece 8, to the wire 9, thence to the coils of the electro- magnet D, and, finally, along the wire 10 to 65 the dynamo.

The electro-magnet C is in a shunt which, as here represented, is formed of a wire 11, extending from the wire 1 to a resistance de- 70 vice or electric lamp 12, a wire 13, extending from the resistance device or lamp 12 to one end of the coils of the electro-magnet C, a wire 14, extending from the other end of the coils of the electro-magnet C to a contact- piece 15, a metallic switch-lever d, and a wire 75 16, leading from the switch-lever to the wire 10. The switch-lever d carries an armature d', which coacts with the electro-magnet D, and has combined with it a weight d² or equiva- 80 lent device for normally holding said lever 80 against the contact-piece 15. So long as the lever d impinges against the contact-piece 15 the electro-magnet C will remain in circuit, and the lever B will, through its contact- pieces b' b², establish electrical communica- 85 tion between the pair of contact-pieces 2 3 and the pair of contact-pieces 7 8.

At any time that the current exceeds the desired limits—as, for instance, by varying the number of lamps in the circuit beyond the 90 limits contemplated for the circuit—the electro-magnet D will become powerful enough to draw the lever d away from the contact- piece 15. Immediately that this occurs the electro-magnet C will be cut out of electric 95 circuit, and the main circuit will be disrupted

by the retraction of the armature B, ensuing upon the cutting out of the electro-magnet C.

Obviously the electro-magnet D and its appurtenances form a cut-out.

What I claim as my invention, and desire to secure by Letters Patent, is—

The combination, with an electric circuit, of a switch, a shunt-circuit serving to close said switch, an electro-magnet in series in the main circuit and serving to open the said

shunt-circuit, and a switch-lever operated by said electro-magnet on an abnormal variation in the current traversing said electro-magnet, substantially as specified.

In testimony whereof I have signed my name to this specification in the presence of two subscribing witnesses.

SIGMUND BERGMANN.
